(57) CLAIM

The ornamental design for a bag, as shown and described.

DESCRIPTION

FIG. 1 is a front view of a bag showing my new design;

FIG. 2 is a rear view of FIG. 1;

FIG. 3 is a left view of FIG. 1;

FIG. 4 is a right view of FIG. 1;

FIG. 5 is a-top view of FIG. 1; and,

FIG. 6 is a-bottom view of FIG. 1.
